MILL

Michael S. Sisulak, Chicago, Ill., assignor to International Harvester Company, a corporation of New Jersey

Application May 29, 1941, Serial No. 395,781

3 Claims. (Cl. 83—11)

This invention relates to a mill of the type commonly used for the reduction or comminution of material such as feed, minerals, or the like.

A conventional form of mill of the type referred to comprises generally an upright drum having upright, spaced side walls, between which is disposed a cylindrical reducing screen, these parts and other enclosing walls forming a material reducing chamber or housing in which is carried reducing mechanism. This mechanism usually takes the form of a rotor having swingable members thereon adaptable to cooperate with a cylindrical screen for pulverizing or reducing the material. A lower portion of the drum is provided with a discharge outlet in the form of a chamber adapted to receive the material reduced in the housing. The discharge chamber is associated with means for moving the material and for discharging the material into storage bins or the like. The present invention is concerned particularly with a mill in which the discharge means is in the form of a means such as a blower fan having a suction connection with the discharge chamber.

In mills of the type just referred to considerable difficulty has been experienced in the operation of the suction means, because of the tendency of the reduced material to pack at the passageway between the discharge chamber and the suction means. Ordinarily one side of the discharge chamber is open to the atmosphere so that the suction means may have a direct draft through the discharge chamber. It has been found, however, that reduced material can and does pile up in the discharge chamber to such an extent that it closes off the air inlet opening, with the result that the suction means fails to remove the reduced material.

The present invention contemplates and has for its principal object the provision of means for eliminating the difficulties referred to above, this means, according to a preferred form of the invention, taking the form of an auxiliary or relief air inlet communicating with the suction means, and adapted to facilitate the removal of reduced material from the discharge chamber or outlet.

An important object is to provide this means in the form of a divider member separating the air inlet opening into two parts, one of which by-passes the discharge chamber and preferably communicates with the suction means at the point of connection of the suction means and the discharge chamber.

Another object is to provide means for ap-

plying suction in two streams, one of which communicates directly with the atmosphere, and the other of which communicates directly with the discharge chamber, it being also an expedient to provide for a communication between the chamber and the atmosphere.

Still another object is to provide, in combination with the means referred to above, deflecting means for deflecting the reduced material away from the air inlet opening which is open to the chamber.

Other and more specific objects of the invention will appear from the following detailed description taken in conjunction with the accompanying sheet of drawings, in which:

Figure 1 is a side elevational view of a mill of a conventional form, portions of the housing structure being broken away; and

Figure 2 is an end view of the same structure taken substantially on the line 2—2 of Figure 1.

The mill chosen for the purposes of illustration is of the type commonly used for milling feed for live stock. As shown in the drawing, the mill comprises generally a lower supporting casing 10 including a drum 11 and a feed inlet means 12. The mill itself is supported on a pair of skids 13, thus elevating the lower portion of the mill slightly above the ground.

As best shown in Figure 2, the drum 11 includes a pair of spaced, upright side walls 14, joined at their upper circular portions by an arcuate wall 15 forming the upper portion of the drum. A perforated reducing screen 16 is disposed within the drum between the walls 14, and forms generally a continuation of the curvature of the arcuate wall 15. The wall 15 extends substantially tangentially to one side of the drum to a point where it meets the feeding means 12. The screen 16 is discontinued a substantial distance about its periphery and is spaced from the inside of the wall 15 to provide a feed inlet throat, generally indicated at 17. A sliding door 18 is adapted to be moved into or out of closed position to close or open the feed inlet throat 17 to the feeder means 12. This door is shown in closed position in the drawings. A portion of the wall 15 immediately adjacent the feed throat 17 is provided with a perforated element 19 to provide means for admitting air to the drum 11 for purposes to be hereinafter described.

The opposite walls 14 serve to journal therein a material reducing means in the form of a rotor 20 of the hammer type. This rotor may be driven by any suitable means such as the pulley 21, and includes a shaft which extends outside of

the housing to drive a suction means in the form of a blower fan 22 carried in a housing 23. This housing includes a conveyer or suction conduit 24 which communicates through an opening 25 in one of the walls 14 with a chamber or compartment 26. This chamber is adapted to receive reduced material through the screen 16. A deflector plate 27 is carried inside the lower portion of the housing 19 and provides means for deflecting reduced material toward the opening 25 which communicates with the suction conduit 24. The material is drawn from the chamber 26 by suction means and is discharged through a discharge conduit in the housing 23, as indicated generally at 28.

The construction just described is generally conventional. The operation of such a conventional mill has heretofore been subject to the difficulties pointed out above, the greatest difficulty being the packing of the reduced material in the area of the opening 25. In the particular form of mill illustrated, it will be noted that a second opening 29 is provided in the other wall 14, this opening being substantially in alignment with the opening 25. The purpose of this opening is to provide an air inlet opening to the atmosphere outside of the mill, so that a direct draft or suction may be created transversely of the drum through the reducing chamber 26. The deflector plate 27 serves to prevent accumulation of reduced material adjacent the opening 29. However, it has been found that a more efficient means was required before the mill would function properly. According to the present invention this means takes the form of an auxiliary or relief conduit, indicated generally in the drawing by the numeral 30. As will be seen from an examination of the drawing, this conduit is provided by the provision of a plate or dividing element 31, which is disposed transversely across the discharge chamber 26. The plate is so arranged that it divides each of the openings 25 and 29 into two parts, the upper parts of each of which are in direct communication with the discharge chamber 26, while the lower parts, indicated generally at 25' and 29', respectively, do not communicate directly with that chamber. There is thus provided an air passage through the opening 25', the conduit 30, and the opening 29', which by-passes the chamber 26 and communicates directly with the atmosphere outside the drum housing 10. In the preferred construction illustrated, the conduit 30 is completed by a floor portion 32. It will be understood, of course, that this portion is not absolutely necessary to an efficient functioning of the means just described. It has been provided in the preferred construction, however, to provide an air inlet outside the mill, whereas, in the absence of such floor, the suction means would draw in air from directly below the plate 31, at which point the air would have a tendency to pick up foreign particles scattered on the ground.

It will be noted from an examination of the drawings that the portion 25' of the opening 25 is located substantially immediately at the junction between the conduit 24 and the discharge chamber 26. According to this feature of the invention, air may be drawn directly through the opening 25' so that a slight suction is created on whatever material happens to be piled up at the opening 25'. Such suction in fact eliminates the accumulation of material at the opening 25, and this air stream, in combination with the deflector 27, serves to keep the opening 29 always

open. In any event, the plate 31 prevents reduced material from clogging that portion of the opening 25 designated at 25', which portion, as has been seen, is absolutely separate from the discharge chamber 26.

As shown in Figure 1, the lower part of the housing 10 is provided with a pair of deflector members 33 which converge from opposite sides of the screen 16 to the receiving chamber 26.

In the operation of the mill just described, material is supplied to the drum 11 through the feeder means 12, the sliding door 18 being at that time moved to open position. The material is reduced in the conventional manner by the action of the rotor 20 on the screen 16, the reduced material dropping downwardly to the receiving chamber 26. The suction fan 22 draws off the reduced material and discharges it through the discharge conduit 23. A constant supply of air to the suction means is insured through either of the open portions 29 or 29'. In the event that the rotor housing becomes choked with material, thus shutting off air which may be drawn through the throat 17, a supply of incoming air is insured by the provision of the perforated inlet plate 19 in the upper part of the wall 15 adjacent the junction between the drum 11 and the feeder means 12. It will thus be seen that there has been provided a preferred form of construction in which a constant supply of air is insured to points in the mill vital to the efficient operation of the mill.

Although the foregoing specification and drawings refer to a mill of the type used in reducing feed or the like, it will be understood that the invention contemplates the provision of the foregoing features in other types of mills and in material reducing machines or apparatus for use in reducing or comminuting other types of materials.

It will be further appreciated that only a preferred form of construction has been illustrated and described and that numerous modifications and alterations may be made therein without departing from the spirit and scope of the invention as defined in the appended claims.

What is claimed is:

1. In a mill including a reducing housing, the combination with the housing of a compartment for receiving reduced material, said compartment having an air inlet and a discharge outlet; a baffle within the compartment for deflecting reduced material away from the air inlet as the material enters the compartment, suction means connected to the discharge outlet for removing reduced material from the compartment, a second air inlet separate from and subjacent the compartment, and means forming a communication between the second air inlet and the suction means and by-passing the compartment, whereby material from the compartment is excluded from said last named means.

2. A mill comprising a drum having upright spaced walls and a cylindrical reducing screen providing a chamber for the comminution of material, a plate disposed transversely across the drum walls below the screen and providing a material-receiving chamber, one of the walls having an opening disposed therein so that the plate divides said opening into two parts with one part outside the confines of the receiving chamber and open to atmosphere, and suction means including a conduit connected over said opening for removing material from the receiving chamber, whereby the suction conduit is

open to the chamber and to the atmosphere outside the chamber.

3. In a mill having a reducing housing, the combination with the housing of a discharge chamber including walls for receiving reduced material, one of said walls having a discharge opening, suction means associated with the chamber through said discharge opening for removing reduced material from the chamber, one of said walls having an air inlet opening nor-

10 mally admitting air to the suction means, means providing two superposed air inlets for two incoming air streams, one communicating with the suction means through the discharge chamber and the other subjacent thereof and communicating directly with the suction means separate from and by-passing the discharge chamber, a partition between said air streams for excluding reduced material from the second air stream.

MICHAEL S. SISULAK.
